CHILD'S VEHICLE

Emanuel Pressner, South Orange, N.J., assignor to Banner Plastics Corporation, Paterson, N.J., a corporation of New York

Filed Mar. 22, 1960, Ser. No. 59,835

Term of patent 7 years

(Cl. D34—15)

FIG. 1

FIG. 2

Fig. 1 is a side elevational view of a child's vehicle according to the invention, the opposite side being identical in all respects to that side shown in this view;

Fig. 2 is a front elevational view of the child's vehicle shown in Fig. 1; and

Fig. 3 is a rear elevational view of the child's vehicle shown in Fig. 1.

I claim:

The ornamental design for a child's vehicle, as shown.
